UNITED STATES PATENT OFFICE.

BENJAMIN ROSENBERG, OF NEW YORK, N. Y.

PNEUMATIC PLUG FOR HEELS.

1,109,180.

Specification of Letters Patent

Patented Sept. 3, 1914.

Application filed January 19, 1914. Serial No. 813,119.

To all whom it may concern:

Be it known that I, BENJAMIN ROSENBERG, a citizen of the United States, and a resident of New York, borough of Brooklyn, county of Kings, and State of New York, have invented a certain new and useful Improvement in Pneumatic Plugs for Heels, of which the following is a full, clear, and exact specification.

This invention relates to a class of devices adapted to be used in conjunction with shoes.

My invention has for its object primarily to provide a pneumatic plug adapted to be inserted in the heels of shoes worn by persons so as to produce a cushion for the tread of the wearer when walking on hard surfaces whereby jarring may be prevented, as well as serving to prevent the wearer from slipping on ice, or snow covered roads, and wherein is provided a body, or plate made of rubber, or other elastic material which is disposed through an opening provided in the top-lifts of the heels of the shoes so as to extend some distance beyond the underside thereof, in order to engage the surface upon which the wearer is walking for serving as a cushion.

Another object of the invention is to provide an air chamber when the plug is applied to a heel by forming a recess in its underside which is closed by the layer of the heel under the top-lift, and this recess has inclined walls to allow for contraction of the body when it is forced through the opening of the top-lift so as to avoid too great a reduction of the dimensions of the air chamber.

A further object of the invention is to provide the cushion with a retaining flange for holding the plug in the heel against accidental displacement.

A practical embodiment of the invention is represented in the accompanying drawings forming a part of this specification in which similar characters of reference indicate corresponding parts in all the views, the said invention being more fully described hereinafter, and then pointed out in the claims at the end of the description.

In the drawing, Figure 1 is a fragmentary perspective view of the heel portion of a shoe with one form of pneumatic plug embodying my invention applied thereto. Fig. 2 is a fragmentary view, showing an inverted side elevation, partly in sec-

tion, of the heel portion of the shoe with the plug applied thereto, the latter being also partly shown in section. Fig. 3 is an enlarged perspective view of the plug. Fig. 4 is a section taken on line 13-13 of Fig. 5 and Fig. 5, is an inverted plan, partly fragmentary, of the plug.

The pneumatic plug may be applied to the usual, or any preferred style of shoe, as 10, having a heel 11 in the central part of the top-lift 12 of which is provided an opening 13 which may be substantially rectangular in shape, or of any other desired form.

The plug has a body, or plate, or cushion 14 which is made of rubber, or other elastic material so as to be similar in the shape of the opening 13 in the top-lift of the heel, and the body is somewhat larger than the opening of the top-lift so as to fit very snugly when disposed therein. The body 14 is formed of a height so as to extend slightly beyond the underside of the top-lift of the heel, and said body has preferably tapered outer edges, as 15, to permit it to be readily inserted through the opening 13 as well as serving to prevent its edges from overlapping the edge of the opening when the pressure from the weight of the person is directed theron.

On the underside of the body 14 is provided a substantially rectangular recess 16 having inclined walls, as 17, to allow for the contraction of the body when it is forced through the opening of the top-lift of the heel so as to avoid too great a reduction of the dimensions of the recess. Extending laterally from the lower edge of the body portion is a retaining flange 18 also made of rubber, or other elastic material, and this flange serves for preventing accidental displacement of the plug from the heel.

In practice the pneumatic plug is applied to the heel of a shoe by forcing the body 14 through the opening 13 of the top-lift 12 before it is attached to the heel so that the flange 18 will lie against one surface thereof and so that the top portion of the body will protrude beyond the opposite surface, as hereinbefore explained. The top-lift is then applied to the other layers of the heel so that the flange will be arranged between the top-lift and the next adjacent layer, after which the top-lift is fastened to the heel in the usual manner. The opening of the recess 16 of the body will

thereby be closed by the layer of the heel which is adjacent to the top-lift, and this recess will then serve as an air chamber. In this manner the elastic body together with the air chamber of the plug will tend to produce a cushion for the tread of the wearer when walking on hard surfaces as well as serving to prevent the wearer from slipping on ice, or snow covered roads.

19 In the foregoing description, I have embodied the preferred form of my invention, but I do not wish to be understood as limiting myself thereto, as I am aware that modifications may be made therein without departing from the principle or sacrificing any of the advantages of this invention, therefore I reserve to myself the right to make such changes as fairly fall within the scope of the appended claims.

20 Having thus described my invention, I claim as new and desire to secure by Letters Patent:—

1. A pneumatic plug of the character described, consisting of an elastic chambered body arranged to be disposed through an opening provided in the top-lift of the heel of a shoe so as to protrude a distance beyond the underside of the top-lift for contacting with the surface upon which the wearer of the shoe may be walking, said elastic body having tapered outer peripheral edges to prevent the protruding part of the body from overlapping the edge of the opening of the top-lift when the pressure from the weight of the person is directed thereon, and means provided on the elastic body, and arranged to be disposed between the top-lift and the adjacent layer of the heel for holding the body against accidental displacement to the heel.

2. A pneumatic plug of the character described, comprising an elastic chambered body arranged to be disposed through an opening provided in the top-lift of the heel

of a shoe so as to protrude a distance beyond the underside of the top-lift for contacting with the surface upon which the wearer of the shoe may be walking, said elastic body having tapered outer peripheral edges to prevent the protruding part of the body from overlapping the edge of the opening of the top-lift when the pressure from the weight of the person is directed thereon, and the wall of the chamber of the body being disposed on an incline so that the elastic body may be forced through the opening of the top-lift to fit tightly therein without materially reducing the dimension of the chamber in the body, and means provided upon the elastic body, and arranged to be disposed between the top-lift and the adjacent layer of the heel for holding the body against accidental displacement to the heel.

3. A pneumatic plug of the character described, consisting of a substantially rectangular elastic chambered body arranged to be disposed through an opening provided in the top-lift of the heel of a shoe so as to protrude a distance beyond the underside of the top-lift for contacting with the surface upon which the wearer of the shoe may be walking, and having means arranged to be disposed between the top-lift and the adjacent layer of the heel for holding the body against accidental displacement to the heel, said elastic body being formed with an outer tapered peripheral edge to prevent the protruding part of the body from overlapping the edge of the opening of the top-lift when the pressure from the weight of the person is directed thereon.

This specification signed and witnessed this seventeenth day of January A. D. 1914.

BENJAMIN ROSENBERG.
